AIR CONDITIONER CONSTRUCTION FOR AUTOMOTIVE VEHICLES

James C. Holby and Robert L. Westrum, Minneapolis, Minn., assignors to D. W. Ovan & Sons, Inc., Minneapolis, Minn., a corporation of Minnesota

Application February 14, 1956, Serial No. 565,403

1 Claim. (Cl. 230—56)

Our invention relates generally to air conditioning apparatus and, more particularly, to improvements in such apparatus utilized in the conditioning of air in the cabs of motor trucks and the like.

An important object of our invention is the provision of an air conditioning unit in which component parts are combined to produce a relatively simple structure which occupies a minimum of space and which is of minimum weight.

Another object of our invention is the provision of a motor including a casing and a single drive shaft having a compressor driving crank on one end thereof and journaled in bearings in the motor casing, and a compressor carried by the motor casing and having a crankcase containing said crank, one of the walls of said crankcase having a drive shaft receiving opening of greater size than said drive shaft whereby said drive shaft is supported only by the bearings in said motor casing.

Another object of our invention is the provision of a motor including a case and a drive shaft having a compressor driving crank on one end thereof and journaled in bearings in the motor casing, and a compressor mounted on the motor casing and having a crankcase containing said crank, one of the walls of the crankcase having a drive shaft receiving opening of greater size than said drive shaft, and a fluid sealing element mounted in said shaft receiving opening and adapted to be lubricated at its opposite sides from the interior of said motor casing and said crankcase.

Another important object of our invention is the provision of motor means having a single drive shaft, one end of which defines a compressor driving crank, and the other end portion of which carries a motor cooling fan, a condenser fan and a drive pulley for an air circulating blower.

Still another object of our invention is the provision of a novel arrangement of a motor cooling fan and a condenser fan whereby the condenser fan not only causes movement of air through the condenser but also aids the motor cooling fan in its function.

The above and still further highly important objects and advantages of our invention will become apparent from the following detailed specification, appended claim and attached drawings.

Referring to the drawings, which illustrate the invention, and in which like characters indicate like parts throughout the several views:

Fig. 1 is a view in top plan of an air conditioning unit built in accordance with our invention, some parts being broken away and some parts shown in section; and

Fig. 2 is an enlarged section taken substantially on the line 2—2 of Fig. 1.

In the preferred embodiment of our invention illustrated, a generally rectangular plate-like supporting member 1 is shown as supporting a housing 2, said housing comprising front and rear walls 3 and 4, respectively,

2

opposed side walls 5 and 6 and a top wall 7. The front wall 3 adjacent the side wall 5 of the housing 2 is formed to provide an intake passage 8 through which air is drawn to the interior of the housing 2. The supporting base member 1 and housing 2 are adapted to be rigidly secured on the roof of the cab of a motor truck or the like, not shown, but in the usual manner.

The air conditioning apparatus mounted on the base plate 1 within the housing 2 involves the several components usually employed in the mechanical refrigeration of air. These component elements do not, in themselves, comprise the instant invention. Hence, for the sake of brevity, detailed showing and description of the same are deemed unnecessary. However, it will be noted that the refrigerating mechanism includes a condenser 9, an evaporator 10, and a pump or compressor 11. These, together with conduit means connecting the same together, and suitable valve mechanism therefor, are well known in the art. In our particular arrangement, the condenser 9 extends transversely of the inlet passage 8, so that air passing inwardly through the passage cools refrigerant moving through the condenser. It will further be noted that the evaporator 10 is situated adjacent the side wall 6 of the housing and extends generally parallel thereto. The evaporator 10 is contained within a separate housing 12 which receives air from a fan or blower 13, the rotor 14 of which is mounted on a shaft 15 journaled in bearings 16 in opposite ends of a blower housing 17. An inlet opening, shown by dotted lines in Fig. 1, and indicated at 18, is adapted to communicate with the interior of the cab, not shown, and through which air is drawn from the interior of the cab to the blower 13. The blower 13 circulates this air through the evaporator 10 from whence it is conducted to the interior of the cab through an outlet opening shown by dotted lines in Fig. 1 and indicated at 19. This arrangement, like the refrigerating apparatus generally, is well known to those skilled in the art, and further showing and description thereof is believed unnecessary.

The pump or compressor 11 comprises a main body 20 defining a cylindrical chamber 21, a head 22 and wall structure defining a crankcase 23, a front wall portion of which is indicated at 24. The compressor further involves a piston 25 mounted for reciprocatory movements in the cylindrical chamber 21, and to which is connected a piston rod 26.

Means for operating the compressor 11 comprises an internal combustion engine or motor 27 including a casing or cylinder block 28 defining a cylinder 29 and a cylinder head 30, and a piston 31 mounted for reciprocatory movements in the cylinder 29. A piston rod 32 is pivotally secured at its upper end to the piston 31 by means of the usual wrist pin 33, and at its lower end to a crank-shaft or drive shaft 34 that is journaled in suitable bearings 35 and 36. The bearing 35 is preferably integrally formed with the cylinder block 28, whereas the bearing 36 is formed as part of an end plate 37 that is bolted or otherwise secured to the rear portion of the block 28. The compressor 11 is rigidly mounted to the rear end of the motor block 28 by means of bolts or machine screws 11', see Fig. 1, with the wall portion 24 being spaced from the end plate 37 of the block 28. The motor 27 is disposed behind the condenser 9, the crankshaft or drive shaft 34 extending forwardly and rearwardly with respect to the base member 1 and housing 2.

A reduced rear end portion 38 of the crankshaft 34 extends through an opening 39 in the crankcase wall portion 24 of the compressor 11 and terminates in a crank 40 to which is journaled the lower end of the compressor piston rod 26 whereby rotation of the crank-

shaft 34 will impart reciprocatory movement to the compressor piston 25.

It will be noted that the opening 39 is generally axially aligned with the bearing 36 and also concentric with the rear end portion 38 of the crank shaft 34 and is of sufficiently greater diameter to define therewith an annular passage communicating with the interior of the motor block 28 and the compressor crankcase 23. With this arrangement it will be seen that the compressor 11 is devoid of bearings for the drive shaft or crankshaft 34 and the shaft 34 is supported at its rear end portion only by the bearing 36. Thus we eliminate to a marked degree the necessity of machining cooperating portions of the compressor casing and motor block to extremely close tolerances, and provide for relatively easy assembly of the compressor to the motor. Inasmuch as the refrigeration system is of the conventional so-called "closed" system, the crankcase 23 must be sealed to atmosphere. Hence, we provide a fluid seal comprising, an annular sealing element in the form of a ring 41 that is mounted in the opening 39 in the crankcase wall portion 24, a metallic washer 42 which encompasses the end portion 38 of the drive shaft 34, a second sealing ring 43 encompassing the end portion 38 of the shaft 34 and in abutment with an annular shoulder 44 defining the inner end of the reduced shaft portion 38, a sealing bellows 45, and a coil compression spring 46, said bellows and spring being interposed between the washer 42 and the sealing ring 43. The ring 41 is stationary in the crankcase wall 24 and a fluid seal is effected therebetween and the housing wall by an O-ring 47. The bellows 45 has fluid tight engagement with the metallic washer 42 and the sealing ring 43, said sealing ring 43 being provided with an O-ring 48. The O-ring equipped sealing ring 43 prevents escape of refrigerant fluid from the interior of the bellows to the interior of the motor or engine block 28, whereas the compression spring 46 exerts sufficient pressure on the washer 42 against the adjacent side of the ring 41 to prevent refrigerant fluid from escaping therebetween to the interior of the motor block 28. It will be noted with reference to Fig. 2 that the side of the metallic washer 42 adjacent the sealing ring 41 is tapered so as to expose a portion of the ring 41 to the interior of the engine block 28, and that the opening 39 between the ring 41 and the compressor crankcase 23 is sufficiently large to expose a portion of the adjacent end of the ring 41 to the interior of the crankcase 23. Inasmuch as the crankcase 23 and the interior of the motor block 28 contain lubricant for the various moving parts therein, both sides or ends of the sealing ring 41 are at least partially exposed to the lubricant which is splashed or otherwise fed thereto. Hence, the ring 41 is well lubricated at all times during operation of the motor and compressor. The sealing ring 41 may be made from any suitable material conventionally used for this purpose, and is preferably impregnated with graphite or like dry lubricant, to insure against failure in the event that lubricant from the crankcase 23 or the interior of the motor does not reach the ring 41.

The front end portion of the shaft 34, indicated at 49, projects axially forwardly through a central opening of an end cap 50 rigidly secured to the engine block 28, and has mounted thereon a flywheel 51. The flywheel 51 is provided with a plurality of circumferentially spaced radial fan blades 52 for the purpose of air-cooling the engine 27. The engine 27 including the flywheel 51 and fan blades 52 is housed within a shroud 53 having an air inlet opening 54 therein concentric with the drive shaft 34 and of sufficient diameter to permit free passage of air to the motor cooling fan blades 52. A driving head 55 is rigidly secured to the flywheel 51 and the front end of the crankshaft or drive shaft 34 by means of a stud 56 and lock nuts 57, and is formed to provide a drive pulley 58. An endless drive belt 59 runs over the drive pulley 58 and a driven pulley 60 mounted fast

on the front end of the blower shaft 15, whereby rotation of the crankshaft 34 is transmitted to the blower fan 14. It will be noted that the drive pulley 58 is of sufficiently smaller diameter than that of the inlet opening 54 of the shroud 53 so as not to interfere with free passage of air from the exterior of the shroud 53 to the motor cooling fan blades 52. A relatively large condenser fan 61 is bolted or otherwise rigidly secured to the front end of the driving head 55 exterior of the shroud 53, and is disposed within the inner end portion of the air inlet 8 directly behind the condenser 9. With reference to Fig. 2, it will be seen that the motor 27 and compressor 11 are supported from the supporting member 1 by brackets 62 and resilient supporting pads 63.

From the above it should be obvious that rotation of the crankshaft or drive shaft 34 will cause the blower 13 to circulate air through the cab of the vehicle and the evaporator 10, and operate the compressor 11 and the motor cooling and condenser fans 52 and 61, respectively. The condenser fan 61 not only is effective to draw sufficient air through the condenser 9 to cause the same to operate in an efficient manner, but also moves the air inwardly through the inlet opening 54 in the shroud 53 at a rate which greatly enhances operation of the motor cooling fan 52. Mounting of the crank 40 and motor cooling and condenser fans on the crankshaft or drive shaft 34 eliminates considerable transmission mechanism and power loss which would otherwise occur therefrom. Thus, by utilizing but a single belt driven element and mounting the several other driven elements on the drive shaft of the motor, a relatively simple and inexpensive construction and a marked improvement in economy of operation is achieved.

Although we have described our air conditioning apparatus as being intended for use primarily in the air conditioning of cabs of motor trucks and the like, it should be obvious that the same can be utilized, without substantial structural change, in the air conditioning of any desired room or chamber, or in refrigeration apparatus, or in any number of instances requiring the use of the components above set forth.

While we have shown and described a commercial embodiment of our device, it will be understood that the same is capable of modification without departure from the spirit and scope of the invention as defined in the claim.

What we claim is:

In a device of the class described, a motor including a drive shaft and a block having spaced bearings in opposed walls thereof journaling the drive shaft for rotation therein, a fluid pump including a casing defining a cylindrical chamber and a crankcase, a piston mounted for reciprocatory movements in said cylindrical chamber and a piston rod carried by the piston and extending therefrom into the crankcase, means mounting the pump casing to the motor block with the crankcase having a wall portion thereof spaced from the bearing in the adjacent wall of the block, said wall portion of the crankcase having an opening therein generally axially aligned with the bearing in the adjacent wall of the block for freely receiving an end portion of the drive shaft, said opening being concentric with and of larger diameter than the end portion of the drive shaft to define therewith an annular passage therebetween with the end portion of the drive shaft being supported only by the bearing in the adjacent wall of the block, a crank carried by the end portion of the drive shaft and disposed thereon within the crankcase and operatively coupled to the piston rod to impart reciprocatory pumping movement thereto upon rotation of the drive shaft, and an annular sealing element mounted in the opening of the wall portion of the crankcase and encompassing the end portion of the drive shaft to close said annular passage, said sealing

element having one side thereof exposed to the interior of the crankcase and another side thereof which is opposed to the said one side being exposed to the interior of the motor block whereby, the opposed sides of the sealing element are positioned to receive lubricant contained within the crankcase and the motor block. 5

CERTIFICATE OF CORRECTION

Patent No. 2,862,652

December 2, 1958

James C. Hoiby et al.

It is hereby certified that error appears in the above numbered patent requiring correction and that the said Letters Patent should read as corrected below.

In the grant, lines 2 and 12, and in the heading to the printed specification, line 5, name of assignee, for "D. W. Ovan & Sons, Inc." read -- D. W. Onan & Sons, Inc. --.

Signed and sealed this 17th day of March 1959.
